UNITED STATES PATENT OFFICE.

ALBERT UDKLER AND JOHAN A. J. SNARTEM, OF RHINELANDER, WISCONSIN.

COVER AND LOCK THEREFOR.

1,033,496.

Specification of Letters Patent. Patented July 23, 1912.

Application filed April 29, 1912. Serial No. 893,898.

To all whom it may concern:

Be it known that we, ALBERT UDKLER and JOHAN A. J. SNARTEM, citizens of the United States, residing at Rhinelander, in the county of Oneida and State of Wisconsin, have invented certain new and useful Improvements in Covers and Locks Therefor; and we do hereby declare the following to be a full, clear, and exact description of the invention, such as will enable others skilled in the art to which it appertains to make and use the same.

Our invention has for its object to provide an improved cover and lock therefor, especially adapted for use on milk and cream cans, and, to this end, it consists of the novel devices and combination of devices herein-after described and defined in the claims.

The invention is illustrated in the accompanying drawings, wherein like characters indicate like parts throughout the several views.

Referring to the drawings, Figure 1 is a view in elevation showing the improved cover and lock applied to a milk or cream can, some parts thereof being broken away; Fig. 2 is a plan view of the same; Fig. 3 is a view in vertical section taken on the line $x^3 x^3$ of Fig. 2; and Fig. 4 is a horizontal section taken on the line $x^4 x^4$ of Fig. 1, on an enlarged scale.

The numeral 1 indicates the body portion of a milk or cream can that is contracted at its upper end, and terminates in an upwardly projecting annular neck portion 2. Surrounding the neck 2 and spaced outward therefrom, is a vertically projecting annular collar 3, which extends both above and below the neck 2. The collar 3, at its lower edge, terminates in an outwardly and downwardly formed extension 4, the lower edge of which is soldered or otherwise secured to the body 1 at the junction with its contracted upper end portion. A horizontally extended flat ring 5 is telescoped over the neck 2 and within the collar 3, and is rigidly secured thereto by solder or otherwise. The ring 5 is located below the upper edges of the neck 2 and collar 3 and forms a channel 6 therebetween. The neck 2 is closed and sealed by means of a cover 7 that is in the form of a hollow disk connected to the collar 3 by means of a single hinge 8 and adapted when closed to snugly fit within the collar 3. When the cover 7 is closed, the top thereof lies flush with the

upper edge of the collar 3. In the bottom of the cover 7 is formed an annular channel 9 in the bottom of which is seated a pliable packing 10 of rubber or any other suitable material. When the cover 7 is closed, the flange 9 projects therein and the packing 10 is pressed into engagement with the upper edge of the flange 9, thereby forming a tight joint between the cover and the can for excluding all dirt and dust from the interior of the can.

For securing the cover 7 closed and against accidental opening in case the can is upset, we provide a lock of novel construction. Said lock comprises a flat spring bar connected to the cover 7 and a co-operating vertically extended headed stud 12 secured to the outer face of the collar 3 diametrically opposite the hinge 8 with its head and neck portion extending thereabove. On the top of the cover 7 is secured by rivets, solder, or otherwise, a flat base or wearing plate 13 on which is mounted the lock bar 11. The lock bar 11 is connected to the wearing plate 13 for pivotal movement and a limited endwise movement by means of a longitudinally extended slot 14 formed in the inner end portion of the lock bar 11, and a headed screw stud 15 extending therethrough and secured to the wearing plate 13. At its outer or free end, the lock bar 11 extends outside of the flange 5 and has rigidly secured thereto a finger piece 16. In one edge of the lock bar 11, just back of the finger piece 16, is formed an L-shaped lock notch 17, the bottom of which extends outward or toward the finger piece 16, and is adapted to receive the headed stud 12. A guide strip 18 overlies the lock bar 11 and its ends are bent laterally downward and anchored to the base plate 13. In some instances, it might be desirable to do away entirely with the base plate 13, in which case the lock bar 11 and guide strip 18 would be connected directly to the top of the cover 7.

To lock the cover 7 in a closed position, the lock bar is first pulled outward to the limit of its endwise movement. Then first, by a lateral swinging movement of the lock bar 11, followed by an inward endwise movement thereof, the lock notch 17 is carried into interlocking engagement with the headed stud 12. At the time the lock bar 11 is carried into interlocking engagement with the headed stud 12, it is necessary to spring the lock bar slightly downward in

order to clear the head of the stud 12, and when released, will be frictionally held thereby under spring tension.

For preventing an unauthorized person from tampering with the contents of the can, an ordinary seal, such as largely used by express companies, is placed around the lock bar 11 and headed stud 12. As shown, this seal comprises a wire 19 with its ends 10 connected by means of a piece of lead 20, or other suitable material.

Our improved cover and lock, as is evident, may be used in connection with other receptacles too numerous to mention, aside 15 from their use in connection with milk and cream cans, as described.

What we claim is:—

1. The combination with a receptacle having a neck portion and a collar surrounding the same and extending thereabove, of a cover adapted to be seated in said collar, a pliable packing on said cover, and means for pressing said packing into engagement with said neck to form a tight joint between 20 the cover and the receptacle, substantially as described.

2. The combination with a receptacle having a neck portion and a collar surrounding the same and extending thereabove, of a cover adapted to be seated in 30 said collar, a channel formed in the bottom of said cover, a pliable packing in said channel, and means for pressing said packing into engagement with said collar to form 35 a tight joint between the cover and the receptacle, substantially as described.

3. The combination with a receptacle having a neck portion and a collar surrounding the same and extending thereabove, of a 40 cover hinged to said collar and adapted to be seated therein, a channel formed in the bottom of said cover, a pliable packing in said channel, and a lock for securing the cover closed and for pressing said packing 45 into engagement with said neck to form a tight joint between the cover and the receptacle, substantially as described.

4. The combination with a receptacle having a neck portion and a collar surrounding 50 the same and extending thereabove, of a cover hinged to said collar and adapted to be seated therein, a channel formed in the bottom of said cover, a pliable packing in said channel, and adapted to be pressed into 55 engagement with said neck to form a tight joint between the cover and the receptacle, a lock projection on said collar, and a lock bar connected to said cover for interlocking

engagement with said projection, substantially as described.

5. The combination with a receptacle having a neck portion and a collar surrounding the same and extending thereabove, of a 60 cover hinged to said collar and adapted to be seated therein, a channel formed in the bottom of said cover, a pliable packing in said channel and adapted to be pressed into engagement with said neck to form a tight joint between the cover and receptacle, a headed stud secured to said collar, a lock 70 bar connected to said cover by a slot and pin connection, and a lock notch formed in said lock bar for interlocking engagement with said headed stud by an endwise and lateral movement of said lock bar, substantially 75 as described.

6. The combination with a receptacle having a neck portion and a collar surrounding the same and extending thereabove, of a 80 cover hinged to said collar and adapted to be seated therein, a channel formed in the bottom of said cover, a pliable packing in said channel and adapted to be pressed into engagement with said neck to form a tight joint between the cover and receptacle, a 85 headed stud secured to said collar, a spring lock bar connected to said cover by a slot and pin connection, and an L-shaped lock notch formed in said lock bar for interlocking engagement with said headed stud by 90 an endwise and lateral movement of said lock bar, substantially as described.

7. In combination with a receptacle and a cover therefor, of a headed stud secured to said receptacle, a lock bar connected to 95 said cover by a slot and pin connection, and a lock notch formed in said lock bar for interlocking engagement with said headed stud by an endwise and lateral movement of said lock bar, substantially as described.

8. In combination with a receptacle and a cover therefor, of a headed stud secured to said receptacle, a spring lock bar connected to said cover by a slot and pin connection, and an L-shaped lock notch formed 100 in said lock bar for interlocking engagement with said headed stud by an endwise and lateral movement of said lock bar, substantially as described.

In testimony whereof we affix our signatures in presence of two witnesses.

ALBERT UDKLER.

JOHAN A. J. SNARTEMO.
